Primary Examiner — Cathron Brooks*Assistant Examiner* — Kristin E Reed*(74) Attorney, Agent, or Firm* — Morgan, Lewis & Bockius LLP**(57) CLAIM**

The ornamental design for an display screen or portion thereof with animated graphical user interface, substantially as shown and described.

DESCRIPTION

This application is related to U.S. Design patent application Ser. No. 29/524,725, entitled “Graphical User Interface of a Machine-Specific Card for a Display Screen or Portion Thereof” filed Apr. 22, 2015; U.S. Design patent application Ser. No. 29/524,726, entitled “Graphical User Interface of a Machine-Specific Offers Card for a Display Screen or Portion Thereof” filed Apr. 22, 2015; U.S. Design patent application Ser. No. 29/524,727, entitled “Animated Graphical User Interface of Transitions between Machine-Specific Cards for a Display Screen or Portion Thereof” filed Apr. 22, 2015; and U.S. Design patent application Ser. No. 29/524,728, entitled “Animated Graphical User Interface of Transitions between a Machine-Specific Card and a Machine-Specific Offers Card for a Display Screen or Portion Thereof” filed Apr. 22, 2015, each of which is hereby incorporated by reference in its entirety.

FIG. 1 is a front view of the first image of an display screen or portion thereof with animated graphical user interface; FIG. 2 is a front view of the second image; and, FIG. 3 is a front view of the third image.

The broken lines illustrate the display screen or portion thereof, portions of the graphical user interface, and portions of an electronic device. None of the broken lines form part of the claimed design.

The appearance of the image transitions sequentially between the images shown in FIGS. 1-3. The process or period in which an image transitions to another image forms no part of the claimed design.
